UNITED STATES PATENT OFFICE.

ISAAC HARTER, OF DONGAN HILLS, NEW YORK, ASSIGNOR, BY MESNE ASSIGNMENTS,
TO FULLER LEHIGH COMPANY, A CORPORATION OF DELAWARE.

FURNACE.

Application filed December 16, 1925. Serial No. 75,676.

My present invention relates to furnaces, particularly those in which the exteriors of the walls which are exposed to the heat of combustion, are cooled by air, and will be best understood from the following description and the annexed drawings, in which Fig. 1 is a sectional elevation of an illustrative form of furnace which I have chosen for purpose of illustration of my invention; Fig. 2 is an enlargement of a portion of one of the walls shown in Fig. 1; Fig. 3 is a view from the left of Fig. 2, with some of the parts broken away; Fig. 4 is a plan view of a cast-iron backing to be described more in detail hereinafter, and Fig. 5 is a section on the line 5—5 of Fig. 4.

Like reference characters indicate like parts in the several views.

In the illustrative embodiment, the furnace chamber is provided with vertically extending walls, all of which may be substantially alike, so that the description of one of them will be sufficient. The wall itself is made up of an inner and an outer portion, the inner portion being made up primarily of refractory tile 10 and 11 arranged in courses, the outer portion 12 being made up of fixed beams 13 to which are fastened vertical members 14, these members being spaced across the wall and the spaces therebetween being filled up in the usual manner with panels 15, these panels preferably being lined with an insulating material.

Extending parallel to the members 14 to form the support for the inner portion of the wall is a plurality of vertically disposed members 16, spaced across the wall and connected to the members 14 by tie members 17 to provide an air space between the inner and the outer portions of the wall.

Each of the tile 10 and 11 has connected thereto so as to be closely in contact therewith, a metallic backing which, as best shown in Figs. 4 and 5, is made up of a backing plate 18 having upstanding edges 19 undercut at 20 with solid portions 21 having holes 21' for the bolts which hold the backing in position, as will be described more fully hereinafter.

On the side of the plate 18 opposite the upstanding edges 19 is a plurality of heat-conducting fins or projections 22 preferably

formed integral with the plate 18 extending outwardly therefrom.

A tile 10 or 11 may be attached to the backing plate in any suitable manner, as, for instance, by forming the tile and then casting the backing around the refractory. Any other suitable method may be used so long as the contact between the refractory and the metal is a close one to permit the heat from the furnace chamber which is taken up by the tile 10 and 11 to be transmitted to the metal backing.

The tile with their backing are assembled to form the wall, with the edges 19 of adjacent tile in contact, the plates 18 being held against the members 16 by bolts passing through holes in the flanges of members 16 and into the holes 21'. The fins 22 extend into the space between the inner and outer portions of the wall and therefore readily radiate into the air in this space the heat which is transmitted through the interior portion of the wall.

Preferably air will be circulated through the space between the inner and outer portions and along the fins or projections 22 and one form of such arrangement is shown in Fig. 1, in which a fan 24 forces air through the duct 25 into the space between the inner and outer portions of the rear wall of the furnace, from whence the air flows along the fins around either side of the furnace, and then along the front, and finally through the openings 26 into the furnace chamber.

In the illustrative form, a powdered fuel burner 27 is supplied by air drawn from the space between the inner and outer portions of the front wall by a fan 28 through a duct 29, the air from the fan being led through the duct 30 to a distributing duct 31, and from thence to the burner or burners, as the case may be. The furnace illustrated is used in connection with a boiler 32.

It will be noted that by the arrangement which I have described, the tile forming the interior face of the wall may be made relatively thin without danger of the wall being destroyed, because the heat transmitted to such tile from the furnace chamber is carried away by the intimate contact between the tile and the backing plate and the air in contact with the large radiating fins.

It will be understood that in my arrange-

ment, the brick would preferably be made of a material having a high heat conductivity, so as to more readily transfer the heat from the front face of the wall to the metallic backing.

It will also be understood that the arrangement which I have described is merely illustrative and that the embodiment of my invention may be widely varied.

10. I claim:

1. A furnace chamber having a vertically disposed wall comprising an inner and an outer portion spaced apart to form an air space therebetween, said inner portion having a plurality of refractory tile, each with a separate metallic backing closely in contact therewith and attached thereto and with the backing away from the interior of the furnace, said metallic backing having 15 projections extending into said air space.

2. A furnace chamber having a vertically disposed wall comprising an inner and an outer portion spaced apart to form an air space therebetween, said inner portion having a plurality of refractory tile, each with a separate metallic backing closely in contact therewith and attached thereto and with the backing away from the interior of the furnace, said metallic backing having 25 projections extending into said air space, and means to circulate air through said space and into the furnace chamber.

3. A furnace chamber having a vertically disposed wall comprising an inner and an outer portion spaced apart to form an air space therebetween, said inner portion having a plurality of refractory tile, each with a separate metallic backing closely in contact therewith and attached thereto and 35 with the backing away from the interior of the furnace, said metallic backing having projections integral therewith and extending into said air space.

4. A furnace chamber having a vertically disposed wall comprising an inner and an outer portion spaced apart to form an air space therebetween, said inner portion having a plurality of refractory tile, each of 45 said tile having a separate metallic backing closely in contact therewith and attached thereto, said backing extending around the sides of the tile, said tile being held with the backing away from the interior of the furnace chamber with the several backings 50 edge to edge, each backing having projections integral therewith and extending into said space.

5. A furnace chamber having a vertically disposed wall comprising an inner and an outer portion spaced apart to form an air space therebetween, said inner portion having a plurality of refractory tile, each of 55 said tile having a separate metallic backing

closely in contact therewith and attached thereto, said backing extending around the 65 sides of the tile, said tile being held with the backing away from the interior of the furnace chamber with the several backings edge to edge, each backing having projections integral therewith and extending into 70 said space, and means to circulate air through said space.

6. A tile for use in a furnace chamber, said tile comprising a brick of refractory material and a metallic plate having one 75 face in contact with one face of the brick and having an upstanding projection surrounding the brick and engaging adjacent edges thereof to hold the plate and brick in contact, the other face of said plate having 80 a cooling fin extending outwardly therefrom.

7. A tile for use in a furnace chamber, said tile comprising a relatively thin metal backing plate, having a recess in one face 85 thereof with its edges undercut, said recess extending over the major portion of the area of the plate, a plurality of lugs extending into said recess from said edges to provide means adapted to engage fastening 90 members, and a refractory tile having a portion thereof in said recess and engaging adjacent undercut edges of the plate to hold the plate and brick in close contact.

8. A furnace chamber having a vertically 95 disposed wall comprising a plurality of refractory tile, each tile having a separate metallic backing closely in contact with the tile and attached thereto and with the backing away from the interior of the furnace, 100 said metallic backing having a projection extending outwardly therefrom.

9. A furnace chamber having a vertically disposed wall comprising a plurality of refractory tile, each tile having a separate metallic backing closely in contact with the tile and attached thereto and with the backing away from the interior of the furnace, said metallic backing having a heat radiating fin 105 extending outwardly therefrom.

10. A furnace wall comprising an inner and an outer portion, a metallic backing on said inner portion having cooling fins extending into the space between the portions, and a plurality of spaced tie members securing the inner and outer portions together.

11. A furnace wall comprising an inner and an outer portion, a metallic backing on said inner portion having cooling fins extending into the space between the portions, 110 a plurality of spaced tie members securing the inner and outer portions together, and a refractory tile supported on said backing and forming the inner surface of said inner portion.

ISAAC HARTER.
